REFRIGERATING APPARATUS

Nelson J. Smith, Dayton, Ohio, assignor to General Motors Corporation, Dayton, Ohio, a corporation of Delaware

Application February 29, 1936, Serial No. 66,460

4 Claims. (Cl. 62—6)

This invention relates to refrigerating apparatus and more particularly to air conditioning means.

It has been found that the circulation of air through air conditioning apparatus often causes many objectionable and annoying noises. These are due to many different causes. Many of these noises may be reduced at their source, but where there are moving parts and the rapid flow of air, there will always be some noises. Many of these noises are amplified by the ordinary cabinet.

It is an object of my invention to provide an air conditioning means which is acoustically treated to prevent objectionable noise.

It is a further object of my invention to provide a metal air conditioning cabinet in which the metal walls are acoustically treated to prevent the amplification of noises originating within the cabinet and also to absorb or suppress noises therein.

Another object of my invention is to provide an improved temperature and humidity control means for a refrigerating system for controlling the temperature and humidity of the air within the room.

Further objects and advantages of the present invention will be apparent from the following description, reference being had to the accompanying drawings, wherein a preferred form of the present invention is clearly shown.

In the drawings:

Fig. 1 is a sectional view of one form of air conditioning means embodying my invention;

Fig. 2 is a vertical sectional view of another air conditioning means embodying my invention;

Fig. 3 is a wiring diagram of the air conditioning means shown in Fig. 2;

Fig. 4 is a fragmentary sectional view showing a modified water flow control means of the apparatus shown in Fig. 2;

Fig. 5 is a vertical sectional view of another form of air conditioning means embodying my invention;

Fig. 6 is a sectional view of the control valve shown in Fig. 5; and

Fig. 7 is a wiring diagram of the form of air conditioning means shown in Fig. 5.

Briefly, I have shown in one form a metal air conditioning cabinet provided with a lower machine compartment, an evaporator compartment and a fan compartment in which the walls of the machine compartment and the fan compartment are acoustically treated by being lined with sound absorbing material. In the second

form of my invention, I have added a re-heating compartment between the evaporating means and the fan compartment so that air may be re-heated to reduce the relative humidity. In this form I also provide a temperature and humidity responsive means for controlling the re-heating of the air which is circulated through the air conditioning means.

In the third form instead of providing a separate re-heating compartment through which the air is passed or around which the air is bypassed, I provide for the passing of compressed gas from the compressor through a re-heating coil or the by-passing of the re-heating coil in order to provide a controllable way of re-heating the air to reduce the relative humidity.

First form

Referring now to the drawings and more particularly to Fig. 1, there is shown an air conditioning cabinet 20 having a metal framework 22 formed of metal angle members joined together by welding or riveting. The cabinet is provided with a machine compartment 24, an evaporating compartment 26 directly above the machine compartment and a fan compartment 28 directly above the evaporating compartment. The machine compartment 24 is formed by sound and heat insulating slabs 30 which are fastened to the framework 22 to enclose the machine compartment. The evaporator compartment is provided with an air inlet 32 beneath the finned evaporating means 34 and an outlet 36 directly above the evaporating means. This outlet is provided with a substantially noiseless fan 38 of a peculiar type which extends into the outlet opening 36 of the evaporator compartment and has its major portion disposed in the fan compartment 28. This fan 38 is directly connected to a fan motor 40 located within the fan compartment, suspended by rubber mountings from the top portion of the framework 22.

Surrounding the framework 22 and supported thereby are outer sheet metal panels 42 which provide the outer metal surfaces of the cabinet. The top panel is provided with a grille 44 directly above the fan through which the air is discharged into the room. The wall 45 which separates the evaporator compartment 26 from the fan compartment 28 is provided with a sound and heat insulating means 46 while the portions of the outer sheet metal panels 42 surrounding the fan compartment 28 are likewise lined with sound and heat insulating material also designated 46.

This material is compressible in its nature and is preferably formed of matted rock wool fibers in the form of thick sheets or blanks. Because of its compressibility it is held tightly between the outer panels 42 and the partition wall 45 to seal the fan chamber 28 from the evaporator chamber 26 against the leakage of air. This insulating material is fastened to the wall 45, the outer panels 42, including the top panel or cover by a suitable adhesive.

Within the machine compartment 24 is a compressor 50 for compressing the refrigerant and for forwarding the compressed refrigerant through a conduit 52 to a water cooled condenser 54 which is in the form of a tank having a water coil 56 therein. The liquid refrigerant is withdrawn from the condenser through the outlet 58 which connects to a filter 60 which in turn is connected by the conduit 62 to an expansion valve 64 located in the evaporating compartment 26. This expansion valve 64 controls the flow of liquid refrigerant to the evaporating means where the refrigerant evaporates under reduced pressure and is returned to the compressor through the return conduit 66. The evaporating means as well as the expansion valve are connected to and supported by the framework 22.

The compressor 50 is driven through pulley and belt means 68 by an electric motor 70 which is pivotally mounted upon the base 72 which also supports the compressor 50. A spring brace 74 tends to turn the motor 70 in a clockwise direction about its pivotal connection to create a tension upon the belt 68. The base 72 which supports the motor 70 and the compressor 50 is supported by a spring mounting 74 extending from the framework 22 of the cabinet. The machine compartment is cooled by a heat transfer member 76 connected to a source of water supply 78. The water is conducted by the conduit 80 to a water valve 82 operated according to condenser pressure to control the flow of water through the water circuit which includes the heat transfer member 76 as well as the water coil 56 within the condenser 54. The valve 82 is connected to the water coil 56 by the conduit 84 and to a drain by the conduit 86.

Normally, the evaporating means operates below the dew point of the temperature of the air which is circulated between the fins of the evaporating means and moisture condenses upon the fins of the evaporating means and drops from the lower edges into a drip pan 88 fastened to the framework 22 directly above the top wall of the machine compartment 24. This drain pan 88 has its bottom sloped toward a drain connection 90. The drain pan also has an extension 92 for collecting any drip from the expansion valve 64. The expansion valve may be adjusted to vary the temperature of the evaporating means so as to control the amount of moisture condensed and the relative humidity of the room cooled as well as to vary the capacity of the refrigerating system.

Second form

In Fig. 2 is another form of air conditioning means in which a room or space to be cooled 120 is shown diagrammatically and which contains a metal air conditioning cabinet 122 having a 70 machine compartment 124, an evaporating compartment 126, a re-heating compartment 128, a by-pass compartment 130, and a fan compartment 132. Within the machine compartment 124 is a compressor 134 driven by an electric motor 75

136 through pulley and belt means 138 for compressing refrigerant and for forwarding the compressed refrigerant through the conduits 140 and 142 to a re-heating coil 144 located within the compartment 128. From the reheating coil 144, the compressed refrigerant is conducted through the conduit 146 to a water cooled condenser 148 containing a water coil 150 having an inlet 152 controlled by a valve 154 operated by the pressure in the compressor discharge conduits 140 and 142 through a conduit 156. Whatever refrigerant is not condensed in the re-heating coil 144 is condensed within the condenser 148 and is conducted to the evaporating means 160 through a conduit 162 under the control of an expansion valve 164 located at the inlet of the evaporating means and provided with a thermoelectric bulb 166 at the outlet of the evaporating means. The evaporating means 160 is connected 20 to the inlet of the compressor by the return conduit 168 which is provided with a solenoid valve 170 which controls the withdrawal of evaporated refrigerant from the evaporator.

The evaporating compartment 126 is provided 25 with an inlet 172 which conducts air to one side of the evaporating means and an outlet directly above the evaporating means in the wall 174 which wall forms the top of the evaporating compartment. Directly above the evaporating means 30 160 is a partition wall 176 which divides the re-heating compartment 128 from the by-pass compartment 130. These compartments each connect directly to the evaporating means. These compartments have a common top wall 178 provided with shutters or dampers 180 at the top of the by-pass compartment 130 and the shutters 182 in the top of the re-heating compartment 128. These shutters are connected by levers and a rod 184 to the damper control motor or device 40 186 located in the fan compartment. This damper control device may be either an electric motor or a fluid pressure device.

The fan compartment 132 is provided with a motor driven fan 188 which draws the air 45 through the inlet 172 in the evaporating compartment through a portion of the surfaces of the evaporating means and thence through either the by-pass 130 or the re-heating chamber 128 into the fan compartment and thence discharges the air through the grille 190 directly above the fan 188 in order to distribute the air in the room. Within the room, there is provided a multiple contact temperature responsive switch means 192 and a humidity responsive switch means 194.

The control of the apparatus is shown in the wiring diagram of Fig. 3. In Fig. 3, there is shown a manually controlled switch 196 for controlling the energization of all the electrical 50 members of the air conditioning system. The fan and the compressor motor circuit are connected in parallel electrical circuit relation with each other and with the remaining circuits of the system. The operation of the fan is controlled by a manual switch 198 in series with the fan, while the operation of the compressor motor is controlled by a low pressure control switch 202 which is responsive to the refrigerant pressure at the inlet of the compressor 134, and which is connected in series with the compressor motor 136.

In the remaining circuit, the temperature responsive switch is supplied with electric energy through the conductor 204 and has a contact 206 which is adapted to connect with the con-

ductor 208 which leads to the damper motor 186 when the room temperature is relatively high and has a second contact 210 which is adapted to close the circuit to the solenoid 170 when the room temperature is high to open the solenoid valve 170 to provide refrigeration to cool the air. When the room temperature is high, this contact 210 is also connected to the damper motor by the electrical conductor 212 in order to cause the damper motor to open the shutters 180 and to close the shutters 182 in order to permit by-passing of the air around the re-heating coil so that the re-heating coil will be substantially ineffective. The damper motor 186 is preferably provided with stop switches to stop the motor when it has reached the limit of its travel in which one or the other of the shutters are closed, while the other is fully open. At low room temperatures the contact 210 is moved to close an electric circuit 214 which is in series with the humidostat 194 and the damper control motor 186 so that when the room temperature is relatively low the relative humidity may be reduced by causing the air to be re-heated after being cooled. By virtue of the fact that the humidostat 194 is arranged in series with the circuit 214, the system is controlled by the humidostat 194 at low room temperatures. Consequently, whenever the room temperature is low and the humidity is high, the system functions as a dehumidifying system directly under the control of the humidostat 194.

In my metal cabinet I have lined the walls of the machine compartment 124 with sound and heat insulating material in the form of slabs 216 while the fan compartment 132 is also lined with sound absorbing material 218. This makes my air conditioning means very quiet since the noises are thereby absorbed.

In Fig. 4 is a modified form in which a compressor 220, a motor 222 and a water cooled condenser 224 are shown in a metal walled machine compartment provided with sound and heat insulating material 226. The condenser 224 differs from the condenser shown in Fig. 2 in that the control of cooling water is by the outlet water and condenser temperature. The condenser 224 contains a water coil 228 connected at its inlet to a water valve 230 controlled by a thermostatic bulb 232 contained in a water chamber 234 at the outlet of the water coil 228 but inside the condenser. The flow of water is therefore controlled by the outlet water and condenser temperature so that the most economical use is made of the cooling water. This may be used in place of the water control system shown in Fig. 2.

Third form

In the third form of my invention shown in Figs. 5, 6 and 7, I have provided an air conditioning cabinet 302 provided with a machinery compartment 304 having sound and heat insulated walls 306 and a cooling and fan compartment 308 also having sound and heat insulated walls 310. Within the cooling compartment 308 is an evaporating means 312 located adjacent the inlet opening 314 of the cooling compartment 308.

Directly in the flow of air at the side of the evaporating means 312 is a re-heating coil 316 for re-heating the air as required after it passes through the evaporating means 312. The air from the room is drawn in through a filter 314, 75 by an internal metal bellows 390 sealed to the

which serves as the inlet opening, through the evaporating means, thence through the re-heating coil 316 by a rather noiseless type of centrifugal fan 318 which is located in cooling compartment 308 and which discharges the air through a grille 320 in the top of the cabinet.

Within the machinery compartment, there is provided a compressor 322 driven by an electric motor 324 under the control of a relay 326. The compressor withdraws evaporated refrigerant from the evaporating means 312 through a suction line 328 and compresses the evaporated refrigerant and discharges the compressed refrigerant to a T-connection 330 from which a conduit 332 extends into a control valve 334.

This control valve is shown in detail in Fig. 6 and has in its lower portion a valve body 336 provided with an inlet connection 338 which connects to the conduit 332, a lower outlet connection 340 which connects to a conduit 342 extending to and connecting with the re-heating coil 316, while in the upper portion there is a second outlet connection 344 which through a conduit 346 connects with the condenser 348 found in the lower portion of the machinery compartment. The valve body 336 is provided with an upper valve seat 350 and a lower valve seat 352. Between the upper and lower valve seat are provided two valve members 354 and 356. These valve members are each formed of a cup-shaped member which contains a rubber-like material such as a polymer of chloro-2-butadiene-1,3, commonly known as "duprene." These valve members are fastened to a valve stem 358 which extends upwardly through the top of the valve housing 336. Threaded to the upper portion of this valve housing 336, is a tubular member 360 to which is fastened at its upper end a pressure chamber 362 which includes a cap member 364 fastened through a ring member 366 to the tubular member 360. This cap member 364 is connected by an annular member 368 to a flexible metal bellows 370 which is closed by a cap member 372 at its upper end. The pressure chamber 362 is formed between the bellows 370 and its cap member 364 on the outside. The interior of the pressure chamber 362 is connected by a flexible tubular conduit means 372a to a thermostatic bulb 374. This thermostatic bulb 374 is surrounded by an electric heater 376 for applying heat to the thermostatic bulb which contains a volatile liquid.

The upper end of the valve stem 358 is connected to a member 378 having an adjustable threaded upper portion including an adjusting screw 380 upon which the cap member 372 rests, and an upper spring retainer 382 which presses against the upper end of the control spring 384. The lower end of the control spring 384 is supported by an adjustable retaining member 386 which is threaded into the interior of the tubular member 360. An access opening 388 is provided in one side of the tubular member 360 so that pins may be inserted into adjusting openings provided in the lower spring retainer member 386 so that through its threaded support the lower spring retainer 386 may be turned to raise it or lower it in order to increase or decrease the tension of the spring 384. The access opening 388 is covered by a cylindrical rubber-like member 388a which also may be formed of duprene or of a high grade of rubber to exclude external air and moisture from the interior of the valve mechanism. The valve stem passage is sealed to the

member 378 at the upper end and to the valve body 336 at its lower end.

When electric energy is applied to the electric heater 376, the volatile liquid in the thermostatic bulb 374 is evaporated so that the vapor passes through the connecting tube 372 to the flexible chamber 362. This exerts a force upon the cap member 372 to compress the bellows 370 and exert a force upon the adjusting screw 380. This force is transmitted downwardly and opposes the natural force of the spring 384 which normally tends to hold the upper valve member 354 in engagement with the upper valve seat 350. When the pressure becomes sufficient to overcome the natural force of the spring 384, the valve stem 358 is moved downwardly so that the lower valve member 356 is moved into engagement with the lower seat 352.

The condenser 358 in the lower portion of the machinery compartment is cooled by a water cooling coil 392 under the control of a pressure operated water valve 394 which has its pressure element connected by a conduit 396 to the T-connection 330 just above the head of the compressor 332. This provides a control of condenser water according to the so-called head or condenser pressure. The liquid refrigerant from the condenser is supplied through a supply conduit 402 to an automatic expansion valve 404 which controls the flow of liquid refrigerant into the 30 evaporating means.

The wiring and control circuits for this air conditioning means are shown in Fig. 7 and include conductors 408 and 410 connected to the source of supply of electric energy. The flow of electric energy is controlled by a manual on and off switch 412. The fan 318 is connected to the supply conductors 408 and 410. Connected in parallel with fan 318 is a second circuit which includes the compressor motor 324 connected in series with a relay operated switch means 326 and a fuse 414. The operation of the compressor motor 324 is controlled by the energization and deenergization of the relay coil 416 which in turn is controlled by a thermostat 418 and a humidostat 420. The thermostat 418 has two simultaneously operated contacts, one of which 422 closes the circuit through the heater 376 to heat the volatile fluid within the thermostatic bulb 374 of the valve 334 when a predetermined high temperature is reached to connect the compressor directly with the condenser. The thermostat 418 also has a second contact means 424 which closes the circuit through the relay 416 and the fuse 414 to close the relay operated switch means 326 to energize the compressor motor 324.

The humidity responsive switch means 420 is connected to the supply conductor 408 in parallel with the contact 424 of the thermostatic switch 418 and is thus effective only when the thermostatic switch 418 is in open position. The thermostat 418 is in the open position only when the temperature is cooled below the predetermined maximum desired temperature determined by the setting of the thermostat 418. The humidostat 420 closes at a predetermined high humidity condition, thus energizing the relay 416 to cause the operation of the compressor motor 324 when the thermostat 418 is in the open position. However, the closing of the humidostat contacts does not energize the heater 376 so that the compressed refrigerant from the compressor is directed by the valve 334, first to the re-heating coil 316, after which the refrigerant passes to the condenser and thence to the evaporating 75

means 312. Thus, when the system is operated in this manner, the humidity is reduced by the condensation of moisture upon the evaporating means but the air temperature is not reduced because of the fact that the air is again re-heated by the re-heating coil 316 before it is discharged back into the room.

Dehumidification under high temperature conditions is accomplished by the evaporating means which during normal operation, as well as during the operation of the heating coil, in addition to cooling the air also condenses moisture from the air unless the air is exceptionally dry. This form of my invention is particularly convenient where the motor compressor condenser unit is located at a considerable distance from the evaporating means and the air duct or room to be conditioned, since only refrigerant conduits are necessary for the connection.

While the form of embodiments of the invention as herein disclosed, constitute preferred forms, it is to be understood that other forms might be adopted, all coming within the scope of the claims which follow.

What is claimed is as follows:

1. In a system for cooling and dehumidifying air for an enclosure, the combination of an evaporator, first and second condenser elements connected in series, means for translating refrigerant from said evaporator to said condenser elements, means responsive to both humidity and temperature conditions of air for varying the operation of said first named means, means whereby temperature conditions within the enclosure further varies the operation of one of said condenser elements, and means for flowing extraneous matter over one of said condensers in accordance with pressure conditions in the high side of said system.

2. In a system for cooling and dehumidifying air for an enclosure, the combination of an evaporator, first and second condenser elements connected in series, means for translating refrigerant from said evaporator to said first and second condenser elements, means for conveying air for the enclosure in heat exchange relation with the evaporator, whereby its dew point temperature is decreased, means for conveying a predetermined portion of the air thus treated in heat exchange relation with the first condenser element, whereby the dry bulb temperature of the air is increased and the first condenser element is cooled, means for circulating extraneous medium for cooling the second condenser element, temperature responsive means for controlling the amount of air flowing over said first condenser and means responsive to refrigerant pressure for controlling the flow of extraneous matter over said second condenser.

3. In a system for cooling and dehumidifying air for an enclosure, the combination of an evaporator, first and second condenser elements connected in series, means for translating refrigerant from said evaporator to said first and second condenser elements, means for conveying air for the enclosure in heat exchange relation with the evaporator, whereby its dew point temperature is decreased, means for causing a thermal exchange between said air and said first condenser element, whereby the dry bulb temperature of the air is increased and the first condenser element is cooled, means for circulating extraneous medium for cooling the second condenser element, temperature responsive means for controlling the amount of air flowing over said first

condenser and means responsive to condensing requirements for controlling the flow of extraneous matter over said second condenser.

4. In a system for cooling and dehumidifying air for an enclosure, the combination of an evaporator, condenser means, means for translating refrigerant from said evaporator to said condenser means, means for conveying air for said enclosure in heat exchange relation with the evaporator, whereby its dew point temperature is decreased, means for conveying air thus treat-

ed in heat exchange relation with said condenser means, whereby the dry bulb temperature of the air is increased and the condenser means is cooled, means for circulating extraneous medium for cooling the condenser means, means for varying the flow of said extraneous medium in accordance with condensing requirements, and means responsive to the temperature conditions of the air controlling the passage of air over said condenser means.

NELSON J. SMITH.
